CLAIM

The ornamental design for a license plate frame, as shown and described.

DESCRIPTION

FIG. 1 is a perspective view of a license plate frame.

FIG. 2 is a front elevation view thereof.

FIG. 3 is a rear elevation view thereof.

FIG. 4 is a first side view thereof, the second side opposite the first side being a mirror image thereof.

FIG. 5 is a top side view thereof; and,

FIG. 6 is a bottom side view thereof.

The mounting flange, front center surface, and rear surface of the license plate frame shown in broken lines form no part of the claimed design.
